UNITED STATES PATENT OFFICE

VICTOR H. HASEK, OF CEDAR RAPIDS, IOWA

COLLAPSIBLE WALLET

Application filed July 26, 1930. Serial No. 470,959.

This invention relates generally to collapsible wallets of the accordion type which are adapted to be conveniently attached to the belt or other part of the person of the wearer, and to contain a variety of articles as desired by the wearer.

The invention has particular reference to wallets of this type adapted for the convenience of fishermen, hunters, and others engaged in the pursuit of sport, which enables a person so engaged to have the free use of both of his hands, and at the same time have readily available the desired tackle or the like.

15 An object of the invention is to provide a device of this character which is capable of being disposed in a highly convenient manner either on the person of the wearer or on another place within convenient reach 20 thereof.

It is another object of the invention to provide a device of this character which is adapted to contain a variety of small articles.

It is an object of this invention to provide 25 a device of this character which, with minor alterations, can be adapted to carry either rifles or gun shells, or fishermen's flies or bait, and any other article or articles desired to be carried in a position to be constantly and 30 readily accessible.

These and other and further objects will be noted, the nature of the invention, its composition, its arrangement and combination of parts will be readily understood by reading the accompanying drawings in connection 35 with the following description.

Figure 1 is a front view of my improved collapsible wallet.

Figure 2 is a back view of Figure 1.

40 Figure 3 is the top sectional view.

Figure 4 is a longitudinal cross section on the line 4—4 of Figure 3.

Figure 5 is a similar cross sectional view on the line 5—5 of Figure 3.

45 Figure 6 is a perspective detail of one of the end plates.

It is understood that I do not limit the application of this invention to the particular embodiment set forth therein. Any 50 change or changes may be made in material

and structure consistent with the spirit and scope of the invention.

Referring in detail to the embodiment used in illustration herein, the numeral 5 generally designates my improved collapsible wallet which is provided with the cover flap 6 to overlap the front of the wallet as shown in Figure 1.

Projecting from the back of the wallet is a spring hook 7 as shown in Figure 2. Referring to Figures 3 and 4 it will be seen that I provide a series of collapsible pockets having substantially rectangular openings indicated at 8 adapted to be collapsed as shown in Figure 5.

65 The bottoms of the pockets are V-shaped, as indicated at 9 and the exterior appearance of said pockets, when opened, presenting the end view similar to that of a wedge. Referring to Figure 4, it will be seen that a frame comprising a pair of "lazy tongs" on each side of said series of pockets, is provided to expand and contract said pockets.

70 Within each end of the wallet is a rectangular plate 10 of the detailed construction shown in Figure 6, comprising a plate portion 10 and continuous flanges 11 disposed about three sides of the plate 10. In the upper part of two opposing flanges is formed a slot 12 for the reception of pins 13 adapted 75 to slidably connect one upper end of said lazy tongs in said slot 12.

75 A hole 14 below the slot 12 is adapted to receive another pin 13a to hingedly attach when lowered said lazy tongs. Similar 85 plates 10 are provided in each end of said wallet and are similarly constructed in all respects. Protruding from a central upper portion of one of the plates 10 and disposed at the rear of the wallet is an outwardly and 90 downwardly bent spring hook 14.

Said hook 14 is provided to permit the wallet to be attached to the belt or other part of the clothing of the person or to other places. Exterior of the framework is a 95 covering 15 of any suitable flexible material or of the same material as the pocket 8.

The lazy tongs is composed of a series of pivoted bars each having an end pivot and a center pivot, the end pivot being design- 100

nated 13 and 13a and the center pivot being designated 13b, said bars crossed at points of the pivot 13b and joined at their outer ends by pivots 13 and 13a, said bars in said position adapted to be moved upon said pivots to accomplish the required accordion movement to expand and contract the pockets of the wallet.

It will be obvious that small changes of the interior material of the pocket will adapt the same for containing fishermen's flies, hunters shells, or other articles required to be ready to hand, and the material of which the pockets and covering are made may be of different flexible materials, may be waterproof, fireproof, or of other character.

It will thus be seen that I have provided a collapsible wallet of the type described, which is convenient in use, which is cheap and easy to manufacture, and which possesses the various features of novelty and improvements resident in its nature and as described in this specification, which renders it admirably adaptable for the purposes for which it is intended.

I claim:

A collapsible wallet of the class described comprising a pair of end plates, a pair of lazy tongs connecting the end of the plates and sides thereof, a flexible open top casing surrounding said end plates and said lazy tongs having a flexible flap closure, and a plurality of flexible receptacles within said end plates and said lazy tongs, said receptacles having rectangular shaped openings and two oppositely disposed sides of each receptacle converging and intersecting forming wedge-shaped pockets.

In testimony whereof I affix my signature.

VICTOR H. HASEK.
